UNITED STATES PATENT OFFICE

CHARLES FAURE-ROUX, OF ST.-CHAMOND, FRANCE, ASSIGNOR TO ETABLISSEMENTS
CH. FAURE-ROUX, OF ST.-CHAMOND, FRANCE

BRAIDING MACHINE

Application filed November 21, 1930, Serial No. 497,189, and in France March 5, 1930.

This invention relates to braiding machines and particularly to this kind of machines adapted to the manufacture of an elastic cord band comprising a core forming a loop and surrounded by a sheath of textile material and having at either end a suitable attaching device, the same being adapted for use as an extensible device or a shock-absorber, for example in aeroplane landing gears. An article of this kind is described in my co-pending application, applied under the No. 441,737 of the 5th of April, 1930. It is an object of my invention to provide a braiding machine for applying a sheath of braided material around a core, comprising at least one carrier adapted to hold said core under tension, means for imparting to said carrier a reciprocating motion, and means for placing layers of thread around said core.

The manufacture of this machine is very simple and inexpensive while its working is economical and sure; on the other hand, in the case of the braiding of cords under tension, it is easy to adjust the tension of the cord by modifying the length of the carrier, a belt for instance.

In the accompanying drawings, which are given solely by way of example:

Fig. 1 is a perspective view of a braiding machine according to the invention;

Fig. 2 is a detail view showing the method of mounting a skein on the belt of the said braiding machine by means of attaching members or plates.

The machine comprises a horizontal table or plate 46 mounted upon uprights 47. A certain number of bobbins 48 are movable by suitable driving means upon the said plate according to the sinuous lines of grooves 49, formed in the said plate. The threads 50 from said bobbins are supported upon two collecting members formed by rings 51-52.

Said machine comprises also a belt 53 stretched between two pulleys 54-55 disposed respectively above and below the plate. The top pulley 54 is the driving pulley and is actuated by a speed reduction device which may consist of gears 60, 61, 62, 63 from a

driving shaft 64. The motion can be reversed by an intermediate pinion 65.

The belt 53, which is provided with a suitable stretcher 66, is interrupted upon a part of its length between the points A and B (Figure 1) in such manner as to receive between these two points the aforesaid extensible device as it is delivered from the said winding machine. For this purpose, each end A, B, of the belt 53 is terminated (Figure 2) by a pair of bent strips 56, 57, which are secured to the belt by an axle 58 placed in an overturned portion 59 of the belt.

When the machine is at rest, the two free ends A and B of the belt are preferably joined to each other by means of hooks or the like whereby the belt will be maintained in its place upon the pulleys.

In operation the ends of plates 100, 101 secured to the extensible device, for instance, to be braided are inserted between the ends of the strips 56, 57 (Figure 2) carried by the belt 53. The said plates 100, 101 can now be connected to the strips 56, 57 by an axle 67. The extensible device is thus inserted into the belt 53 and since the length A, B, of the belt, (which can be adjusted by the stretcher 66) is equal to the distance between the holes of the plates 100, 101 mounted on the thimbles 2. The extended elastic apparatus, when attached to the belt, will maintain its tension.

Now, the manufacture of the sheath is proceeded with. The belt 53 is vertically raised and then lowered, (by means of the reversing device) and the threads 50 from the bobbins 48 will thus be made to travel the whole length of the skein, in both directions, and the sheath can thus be given several thicknesses.

Having now described my invention what I claim as new and desire to secure by Letters Patent is:

1. A braiding machine for applying a sheath of braided material around a core comprising a flexible carrier adapted to be put under tension, means for securing between the ends of said carrier the said core, pulleys supporting said carrier, means for rotating said pulleys alternately in opposite direc-

tions, means for placing layers of thread around said core.

5 2. A braiding machine for applying a sheath of textile material around an elastic loop under tension comprising a flexible carrier, adapted to be put under tension, means for securing between the ends of said carrier the elastic loop under tension, pulleys supporting said carrier, means for rotating said 10 pulleys alternately in opposite directions and means for placing layers of thread around both strands of the elastic loop under tension.

15 3. A braiding machine for applying a sheath of textile material around an elastic loop under tension comprising a flexible carrier, adapted to be put under tension, means for securing between the ends of said carrier the elastic loop under tension, pulleys supporting said carrier, means for rotating said 20 pulleys alternately in opposite directions, means for placing layers of thread around both strands of the elastic loop under tension, and means for adjusting the length of said carrier.

25 4. A braiding machine, for applying a sheath of braided material around a core, comprising at least one carrier adapted to hold said core under tension, means for imparting to said carrier a reciprocating motion, and means for placing layers of thread around said core.

In testimony whereof I have signed my name to this specification.

CHARLES FAURE-ROUX.
